SUPPORTED MANIKIN

Filed Oct. 18, 1928

UNITED STATES PATENT OFFICE

ALBERTIA MAE SUMNER, OF DAYTON, OHIO

SUPPORTED MANIKIN

Application filed October 18, 1928. Serial No. 313,313.

This invention relates to a manikin or model such as is used in dressmaking or related arts. More specifically it relates to a sheet metal manikin which can be used for display purposes or demonstrating purposes in a manner which will be clearly understood hereinafter.

In manikins hitherto used complete, practical, results were not obtainable. The manikin itself was unstable and weak and no means were provided for properly draping or displaying it. In addition, the manikin itself was unattractive and thus no aid in the desired functions.

15 Among the objects of my invention, therefore, are: the provision of a strong, simple, and effective manikin; the provision of a manikin cheaply made in few operations; the provision of a manikin readily assembled 20 and disassembled; the provision of a manikin attractive in form which permits draping or displaying; and a manikin to take the place of existing manikins which will be admirably adapted for the purposes and operation for which it was designed.

For the attainment of the foregoing objects and such other objects as may herein-after appear or be pointed out, I have illustrated the preferred embodiment in the accompanying drawings wherein:

Figure 1 is a front elevation of the manikin of my invention assembled with the supporting stand;

Figure 2 is a side view of the invention of Figure 1 looking toward the right side thereof, but without the head which has been omitted as unnecessary for this view;

Figure 3 is a section on the line 3—3 of Figure 1; and

40 Figure 4 is a section on the line 4—4 of Figure 1.

Similar numerals refer to similar parts throughout the several views.

Referring to the drawings in detail it will be seen that the members of the manikin itself are of sheet material. Any desired material may be used but preferably stamped metal members are used as these best serve the ends of the invention. The thickness is also a matter of choice but practically

is such as to give the desired strength and rigidity without undue bulk and weight.

The manikin itself has a body or torso member 1 which is an elongated piece substantially in the outline of a human figure having a narrowed waist portion 2 as shown. Centrally of the upper end of this body member a neck 3 and head 4 arise therefrom in the usual relation. The head 4 has painted or impressed thereon or therein features representative of a human face. The periphery of the head is covered by suitable material secured thereto, as by glue, shaped to represent a desired type of haircut.

Secured to the lower end of the body member 1 are the legs 5 and 6 associated in overlapping relation as shown to give strength and neatness to the figure. The rivets or screws 7 and 8 serve to unite the legs to the body member while the rivet or screw 9 unites overlapping portions of the legs. The choice of securing means depends on whether a permanent or demountable structure is desired. In the former event rivets are used, in the latter screws. Again some securing means may be one and some the other as will clearly depend on conditions. The showing of one or the other is not intended to be limitative to that one alone but is purely illustrative. The bottom of the legs terminate in foot shaped portions representing shoes worn thereon as at 10 and 11. These shoes may be similar to the material constituting the haircut above-mentioned, or either or both may be represented in any suitable manner by actual goods or leather or hair, respectively, or merely by paint or any manner of impression in the material of the manikin. It is most important to have graceful, attractive, appearance to the manikin such as is delineated by the shapes and positions of the parts shown.

This includes also the arm members which will now be described in detail. Each arm is shown as comprising two substantially equal portions jointed together by a pivot 12 and representing the forearm 13 and upper arm 14. Each upper arm 14 is pivoted to an upper corner of the body member 1 at 15. The lower ends of the forearms 13 are shaped to represent hands and may be in any desired

position. It is understood that any portion of the manikin may be ornamented or colored as desired without departing from the scope and spirit of my invention.

5 It will further be noted that the body or torso member is provided with perforations 16. These are important as is likewise their disposition. By means of such perforations goods may be sewed to the body member and 10 suitably draped to represent the garment in question and the style thereof. In this manner it can be seen how said garment will appear when worn and experimentation may be carried on as well. Any garment or kind of 15 apparel may be represented without limit. It is also obvious that any type of figure from tall and slender to short and stout may be utilized with great advantage. Also any form may be used whether man, woman, or 20 child with equal success, and even animals may be represented if desired. Duplication and proper arrangement would permit any desired grouping also to be shown. It is distinctly intended that the locations of the 25 perforations be only illustrative and that any number may be used in any location whatever. By legitimate extension thereof the principle may be extended to the arms, legs, head, feet, or other locations for analogous 30 uses.

Below the narrowed waist 2 of the body member and secured to the rear surface thereof is the strap member 17 riveted or screwed at 18 and 19. The ends of the strap member 35 directly abut the rear surface of the body member but the central portion 20 of the strap member is bent or raised so as to form a space 21 as clearly shown in Figure 3. The purpose of this space will be apparent 40 hereinafter.

45 In order to present the manikin to view in a natural, graceful, yet firm and stable upright position, the stand or support shown is provided for cooperation therewith. This stand comprises a heavy or weighted base 22 and an upstanding rod 23 associated therewith in any suitable manner. The top of the rod is flattened and enlarged as shown in any desired manner or a plate may be secured to the rod, if preferred. This enlarged flattened position is shown at 24. It is proportioned so that it fits within space 21 hereinabove mentioned with a firm fit. A rib 25 on portion 24 may serve to make 50 a tight friction fit with a wedging action making accidental withdrawal improbable.

55 It is clear that to assemble the manikin and stand the manikin is lowered next to the stand so that plate 24 passes into space 21. Enough downward pressure is exerted to make a firm fit. To disassemble, the manikin and stand are merely pulled apart.

60 It is equally clear that the manikin itself 65 may be easily assembled if screw connections

are used, whereas it is always ready for use if permanent rivets are utilized.

It is thought that all details of operation and use have been so thoroughly explained or will be so evident that recapitulation is 70 not required.

75 All the above matters are intended to be more illustrative than limitative so that I do not limit myself thereto except as contained in the subjoined claims.

Having thus described my invention and illustrated its use, what I claim as new and desire to secure by Letters Patent of the United States is:

1. In combination, a sheet metal body member in the form of a human torso with a head at the central upper end, sheet metal leg members arranged in partially overlapping relation united at their upper ends to the lower end of said body member, said leg members being united to each other through the overlapping portions, sheet metal arm members pivotally united to the body member at the upper corners thereof, said arm members being additionally pivoted approximately midway of their length, a metallic strap member secured to the back of the body member and provided with a raised central portion, a stand comprising a weighted metal base and an upstanding metal rod, the upper end of said metal rod being flattened for reception under the raised central portion of said strap member aforesaid. 80 85 90 95

2. In a device of the character described, an elongated metal body member in the form of a human torso having perforations therein at predetermined locations adjacent curved portions of the body member whereby flexible material may be sewed thereto as desired, there being a head surmounting the body member on which are delineated suitable features, the head being further provided with material secured thereto representative of human hair in any prevailing mode of cut. 100 105 110

3. In a sheet metal manikin representing a human female form in outline, a sheet metal torso member, a metal strap united to the rear surface of said torso member, said strap having a central portion spaced from the torso surface and providing a space for the reception of a supporting member having a wedge end insertible in said space, said torso being provided with a plurality of series of perforations at predetermined locations adjacent torso member curves. 115 120

4. A device of the character described comprising a body member, leg members, detachable single coupling elements connecting said leg members to said body member, connecting means for the legs for holding the same in a predetermined position relative to one another, said connecting means comprising a single element, arm members pivot- 125 ed to the body member, a stand, and comple- 130

mentary means on said body member and stand for maintaining the whole in upright position.

5. In combination, a body member, leg members detachably united thereto, connecting means for the legs for holding the same in a predetermined position relative to one another and located below the bottom of said body member, each of said means for detachably uniting said leg members with said body member and said connecting means for the legs comprising a single element, jointed arm members pivoted to the body member at the upper part thereof, a stand comprising a weighted base and an upstanding rod, and means on the back of said body member to receive the end of the rod, whereby the whole is maintained in an upright position.

10 In testimony whereof I hereunto set my hand this 8th day of October, 1928.

20 ALBERTIA MAE SUMNER.
